UNITED STATES PATENT OFFICE.

JAMES T. CASEBEER, OF WASHINGTON, DISTRICT OF COLUMBIA.

GAME.

1,116,012.

Specification of Letters Patent.

Patented Nov. 3, 1914.

Application filed November 20, 1911. Serial No. 661,212.

To all whom it may concern:

Be it known that I, JAMES T. CASEBEER, a citizen of the United States, residing at Washington, District of Columbia, have invented certain new and useful Improvements in Games, of which the following is a specification.

This invention relates to a new and useful improvement in games, more especially to that class in which there is a step by step movement from the starting point to a goal, with safety points and premiums for certain moves, one of which in the present instance, is a grand prize obtaining the goal in one movement.

In the drawing: Figure 1 represents a portion of the map of the city of Washington, District of Columbia, showing streets and avenues and certain of the public buildings and parks being indicated, as many being indicated as will suffice for the purpose of this invention. Fig. 2 represents the device folded for transportation.

In view of the fact that the drawing shows a portion of such map, the usual indications will not be employed but the game described without any preliminary statement of the details of the figures, as they will duly appear in describing the game.

For the purpose of indicating the moves of each player, there may be used one kind of an indicator, such as a tee totum, marked by the numeral 1. This may have any number of pointers 2, to be numbered in sequence. On some place on the board this indicator is to be located and some location is assigned as that to which a pointer must point to show what moves, if any, are to be made. For instance, if the indicator is located on Lafayette Square, the corner of Pennsylvania avenue and 15th street may be assigned as the location toward which the pointer must point to show what move is to be made, and as many moves may be made as the number on the pointer indicates. Should there not be any pointer pointing to this location the move is lost.

The pointer device may be used for games of different designation and rules.

In the present instance the game is designated "The Race to the White House." Names of several Presidential candidates, which may be the names of men already suggested as Presidential candidates, or already nominated, may be placed upon playing cards; or the playing cards may be so

designated without names being placed upon them, as by colors, or otherwise.

The starting point may be supposed to be the Cosmos Club, just opposite the northeast corner of Lafayette Square, at the corner of H street and Madison avenue. The White House is the goal. The route of travel will be from the "Cosmos Club," at H street and Madison avenue, southwardly to Pennsylvania avenue, eastwardly to 15th street and New York avenue, northeastwardly on New York avenue to K and 9th streets, at the Public Library; eastwardly on K street to 7th street and Massachusetts avenue; southeastwardly on Massachusetts avenue to the Union Station, at 1st street northeast; southwardly to B street southeast, at corner of the Congressional Library and Capitol grounds; thence westwardly on B street to 1st street southwest; thence north on 1st street to Garfield Monument and Pennsylvania avenue and 1st street northwest at the Peace Monument; thence westwardly on Pennsylvania avenue to 15th street northwest; thence northwardly on 15th street to the corner of 15th street and New York avenue northwest; thence westwardly on Pennsylvania avenue to the White House.

In this game each street crossing is a step and counts one in the game. For instance, in starting, passing from the starting point at the corner of H street and Madison avenue to Pennsylvania avenue is one step, from this point to 15th street and New York avenue is one step; from 15th street and New York avenue to K and 9th streets is six steps, etc.

Certain of the more prominent streets, such as 11th, 7th, East Capitol, B street southeast, 1st street southwest, may be made danger points, upon arriving at which the player will be turned back a predetermined number of steps.

The Public Library, on K and 9th streets, the Union Station at Delaware avenue, the Congressional Library, Garfield Monument or the Peace Monument, the Treasury Department, 15th street and Pennsylvania avenue northwest, may be premium points, upon arriving at which the player will be given a predetermined number of advance moves.

An important feature of this game is the grand prize. There is to be placed upon the spindle of the tee totum, an angle bar 3,

the angle being such that one arm will point to the starting point and the other to the goal. This angle bar should be adjusted so as to be held tightly enough upon the spindle to be rotated when the tee totum is spun and yet loose enough to permit gravity to keep it from revolving exactly with the tee totum. The result will be that there is no certain relation between the arms of the 10 angle bar and the points of the indicator.

The grand prize is to be given to the player who turns the indicator so that when it stops moving one arm of the angle bar will point to the starting point and the 15 other to the goal. And the grand prize is the game. That is, the player who succeeds at any play in having the angle bar point to both the starting point and the goal wins the game. Otherwise the player must move 20 his man from point to point the number of steps indicated by the points of the indicator.

Having described my invention, what I claim is:

25 1. In a game apparatus, a board having

thereon a starting point, a goal and intermediate stations, in combination with an indicating device for indicating at one move the goal and the winning of the game.

2. In a game apparatus, a board having 30 thereon a starting point, a goal and intermediate stations, in combination with an indicating device consisting of two parts, one for indicating the stations and the other for indicating, at one move, the goal. 35

3. In a game apparatus, a board having thereon a starting point, a goal and intermediate stations, in combination with a movable indicator having a device attached thereto, but not moving synchronously 40 therewith, the indicator being adapted to indicate the moves of the game and the device attached to the indicator being adapted to indicate the goal.

In testimony whereof I affix my signature 45 in presence of two witnesses.

JAMES T. CASEBEER.
